Atty.

UNITED STATES PATENT OFFICE

91,355

DESIGN FOR A SIGN

Herbert G. Hammar, Chicago, Ill., assignor to Federal Electric Company, Chicago, Ill., a corporation of New York

Application November 15, 1933. Serial No. 49,733

Term of patent 14 years

To all whom it may concern:

Be it known that I, HERBERT G. HAMMAR, a citizen of the United States, residing at Chicago, Cook county, Illinois, have invented a new, original, and ornamental Design for a Sign, of which the following is a specification, reference being had to the accompanying drawing forming part thereof, showing my new design.

I claim:

The ornamental design for a sign as shown.

HERBERT G. HAMMAR.
